UNITED STATES PATENT OFFICE.

MAX C. WHITMORE, OF DAYTON, OHIO.

ROTARY EXPLOSIVE-ENGINE.

1,279,195.

Specification of Letters Patent: Patented Sept. 17, 1918.

Application filed November 22, 1915. Serial No. 62,687.

To all whom it may concern:

Be it known that I, MAX C. WHITMORE, a citizen of the United States, residing at Dayton, in the county of Montgomery and State of Ohio, have invented certain new and useful Improvements in Rotary Explosive-Engines, of which the following is a specification.

This invention relates to new and useful improvements in rotary explosive engines.

The principal object of the invention is to provide a rotary explosive engine of perfect balance, for accomplishing in a more facile and economic manner, the work which the 15 reciprocating type of explosive motor now performs. Furthermore, the peculiar construction and arrangement of my improved engine equips it for many uses, such as aeroplane propulsion, for which the present type 20 of explosive motor is not efficiently adapted.

Among the many advantages of my explosive turbine are simplicity and efficiency of construction and operation, economy of space, and the absence of valves, gears and 25 other parts which are so often the source of trouble, noise and loss of power in reciprocating motors.

Other important and incidental objects will be brought out in the following specification and particularly pointed out in the 30 subjoined claims.

The preferred form of embodiment of my invention is illustrated in the accompanying drawings, of which Figure 1 is an elevational view, in section, of my improved rotary explosive engine. Fig. 2 is a sectional view thereof taken on the line $a-a-a$ of Fig. 1. Fig. 3 is an elevational view of the cylinder head through which the spent gases 35 are exhausted. Fig. 4 is an elevational view of the cylinder head through which the explosive mixture is admitted to the cylinder. Fig. 5 is a section taken on the line $b-b$ of Fig. 2, showing one of the packing pieces in 40 its normal position. Fig. 6 is a sectional view of one of said packing pieces in its extended position on its respective blade. And Fig. 7 is a sectional view taken on the line $c-c$ of Fig. 1, showing the gas reinforcing 45 chamber provided in the cylinder shell.

Throughout the specification and drawings similar reference characters refer to corresponding parts.

In a detailed description of the preferred 50 form of embodiment of my invention, the numeral 1 designates a cylindrical shell pref-

erably constructed of cast iron and having a preferably integral head portion 2. The shell 1 has formed on its outer periphery a series of lugs 3. Similar lugs 4 formed on a 60 cylinder head 5, are adapted to receive bolts 6 passed through the lugs 3 to firmly secure said cylinder head to the open side of the shell 1. (See Figs. 2, 3 and 4). Two oppositely disposed feet 7-7 formed on the shell 65 1, are adapted for connection by the bolts 6, to corresponding feet 8-8 formed on the cylinder head 5, to provide means for firmly securing the cylinder to a standard or other suitable support. 70

The cylinder heads 2 and 5 have their central portions turned outwardly to provide bearings 9 and 10 respectively, preferably of the ball type as shown in Fig. 2, for a rotary shaft 11. 75

The bore of the shell 1 is such as to provide a smooth inner surface 12 which is approximately elliptical in cross section and whose minor axis is represented by the line $a-a-d$. For rotation within this bore there 80 is secured to the shaft 11, by means of a key 13, the core 14 of a rotary piston 15. This piston is circular in cross section, and of a diameter which permits its periphery to slidingly engage the inner surface 12 of the shell 1 at its narrowest points, which are at the intersection of that surface with the minor axis $a-a-d$ of said shell (see Fig. 1). 85

For a purpose to be hereinafter described, there is formed in the piston 15 between its core 14 and an annular partition 16, a cavity 17 which extends well into, but not through, said piston from the side thereof which adjoins the cylinder head 5. Between the partition 16 and the outer rim 18 of said piston, 90 an annular cavity 19 is also formed for a purpose to be likewise explained. This cavity extends farther than the cavity 17, into the piston 15, but not entirely through the latter. 95

The piston 15 has one open side, which is adapted to be closed by a circular plate 20. As will be observed from Fig. 2, this plate is firmly held against the piston by screws 21 which, after being passed through the partition 16, receive nuts 22 that are preferably pinned thereto in recesses 23 provided in the piston side. 100

Formed in the rim portion 18 of the piston 15 is a series of radial channels or 110 grooves that receive blades or wings 24 to be hereinafter described. Each of these grooves

extends from the periphery of the piston to the annular cavity 19, and between a narrow wall 25 of said piston and the plate 20. Opposite each of these grooves are three smaller ones provided in the annular partition 16, through which the leg portions 26, 27 and 28 of each blade 24 loosely project into the cavity 17. Each blade is so constructed that a coil spring may be placed around the middle 5 one of said legs and between the other two, with the partition 16 as a fixed support. Recesses 29^a formed in the piston rim 18, insure a free movement to the upper ends of said springs. Accordingly, when placed under 10 tension, these springs 29 will force the blades 24, which are movable, outwardly and against the inner surface 12 of the shell 1 at all times.

When the piston 15 rotates, it is, as before 20 stated, only in engagement with the inner surface 12 of the shell 1 at two places, namely, the intersecting points of said surface with the minor axis of the shell. On the other hand, the springs 29 are tensioned to 25 maintain the blades 24 in sliding contact with the inner surface of the shell at all times. The tension of said springs, however, is just enough to cause the blades to graze the surface 12 at the widest points of 30 the shell, centrifugal force supplying any additional drawing power that may be necessary to extend the blades to said surface at all times. For the purpose of lessening friction, it is important that the blades be not 35 too tightly pressed against the surface of the shell; hence the springs are tensioned as above explained.

As will be observed from Figs. 1 and 2, there is formed on one side of the minor axis 40 $a-a-d$, between the inner surface of the shell 1 and the outer periphery of the piston 15, a gas passage 30; and on the other side of said axis, a similar passage 31. Each passage is widest on the line of the major axis 45 $e-e$, becoming narrower on each side thereof as the minor axis $a-a-d$ is approached.

The passages 30 and 31 are sealed by the cylinder heads 2 and 5 except at the places now to be described. Referring to Fig. 4, 50 it will be observed that a tube 32 leads from a carburetor supporting plate 33 to an intake chamber 34 secured to the cylinder head 5. Through an opening 35 therein, represented by dotted lines in Fig. 4, an explosive 55 mixture may enter the passage 30 just beyond the point of intersection of the lower part of the minor axis $a-a-d$ with the inner surface of the shell 1.

Preferably formed in the rotary piston 15, 60 at equal distances apart, are four peripheral pockets 36, 37, 38 and 39, semi-circular in cross section. Of the blades 24 there are eight, spaced an equal distance apart, and between each two there is one of the said 65 pockets.

Each time a pocket passes the gas inlet opening 35, it will receive a charge of the explosive mixture. In addition, the blades 24, being centrifugally and spring pressed against the inner shell surface 12, will, as 70 they pass this point, also receive between them a part of the charge. After the major axis $e-e$ is passed, the passage 30 becomes narrower, whereupon the gas inclosed between the blades will be compressed between the converging walls of the passage. 75

Provided in an enlarged portion 40 of the cylindrical shell 1, in communication with the passage 30 and a little to one side of the minor axis $a-a-d$, is a gas receiving 80 chamber 41, preferably semi-circular in cross section. After a gas pocket, for instance the pocket 38 in Fig. 1, has passed the chamber 41, the latter is in full communication with the passage 30. It therefore results that the compressed gas between the blades which follow, having no other means of escape from the narrowing passage walls, will enter and be compressed within this chamber 41. When the blade immediately 90 ahead of the next gas pocket, which in the present instance in the pocket 37, clears said chamber, the greater part of the compressed charge in the latter will be added to that in the pocket, to approximately double it. 95

Provided on the enlarged portion 40 of the shell 1, and communicating with the passage 31 a short distance beyond the top part of the minor axis $a-a-d$, is a spark plug 42. The plug is so timed as to ignite the 100 compressed mixture immediately a gas pocket is centrally beneath it, whereupon the resulting explosion will exert its force against the blade in front, to rotate the piston 15. The explosion of the compressed 105 gas every time a pocket passes the spark plug 42, insures a uniform continuous movement to the piston. As the number of these pockets is four, the engine is capable of great driving power, especially in view of 110 the fact that each compressed charge is practically doubled by the receiving chamber 41 hereinbefore described. For the latter purpose two blades are disposed between each pair of adjoining pockets, to collect and 115 compress the reinforcing charge for the pocket behind. Furthermore, the sweep of the blade which receives the force of the explosion, from the spark plug 42 to the opposite end of the passage 31, is of such length, 120 and the leverage so great, as to materially aid in the development of power in the motor.

The burnt gases resulting from each explosion, are swept by the blade behind, into 125 an outlet port 43 leading through the cylinder head 2 into an outlet pipe 44. (See Fig. 3).

For the purpose of preventing leakage of the explosive mixture past the sides of the 130

blades 24, packing pieces 45 and 46 are provided. As shown in Figs. 5 and 6, the sides of each blade are triangular in cross section to loosely enter the similarly recessed sides 5 of the packing pieces 45 and 46. These pieces fit in elongated notches formed in each blade above shoulders 47, being held therein by the latter and the side walls of the piston. When subjected to the pressure 10 of the gas in front of, or behind, the blade, the piece 45 will be forced against the wall 25 of the piston, and the piece 46 against the outer portion of the plate 20, to prevent leakage at those points. In other words, the 15 pressure of the gas will force said pieces along the beveled edges of the blade, from their normal positions shown in Fig. 5, to their extended positions shown in Fig. 6.

Referring to Figs. 2 and 7, it will be observed that the outer periphery of the narrow wall 25 of the piston 15 is beveled on its inner side to receive a split ring 48 which is also triangular in cross section. On one side this ring faces the packing pieces 45, and 25 when subjected to pressure, it has the same relative movement along the beveled edge of the wall 25 as they have along the beveled edges of the blades. However, while the packing pieces are only forced outwardly, 30 the ring 48 will be forced upwardly and outwardly to seal any opening that may exist between its respective side of the piston and shell.

Again referring to Figs. 2 and 7, it will be observed that the outer interior edge of the plate 20 is notched to loosely receive a split rectangular ring 49 which extends a short distance into an annular notch formed in the flange portion 50 of the cylinder head 40 5. When subjected to pressure, this ring will likewise be forced upwardly and outwardly to seal any opening that may exist between the plate 20 and the shell.

It will now be seen that the sliding movement of the packing pieces 45 and 46, induced by pressure, will prevent leakage past the blades, while the upward and outward movement of the piston rings 48 and 49, likewise induced by pressure, will seal the 50 openings between the piston and the shell. To accomplish their purpose more effectually, the above named moving parts may be constructed wholly or in part of suitable packing material.

The operation of the engine is as follows: The explosive mixture, which may consist of any suitable hydrocarbon fluid that has been properly carbureted, is admitted through the inlet port 34 into the passage 30 in the shell 1. As a gas pocket 36, 37, 38 or 39 passes this port, it, as well as the space between the passing blades 24, is filled with gas. These blades 24, which, as before stated, extend at all times to the inner surface 12 of the shell, sweep the admitted gas

into the narrowing portion of the passage 30, where it is compressed.

To the gas in each pocket there is added that which has been stored in the chamber 41 as before described. The reinforced 70 charge in each pocket is ignited when the latter comes centrally below the spark plug 42, the resulting explosion sending the pocket and blade in front, through a cycle that could hardly be equaled in a reciprocating 75 engine. Each of the pockets induces a separate explosion, making four for one revolution of the piston. However, more pockets and blades may be provided, or a less number employed, without departing 80 from the spirit of my invention.

After each explosion, the spent gases are swept by the blades behind, into the outlet port 43.

While my improved device is designed 85 primarily as an engine, it may, with but slight modification or alteration, be made to apply equally well to an air compressor or pump. In its gears, valves and accompanying parts are noticeably lacking. This 90 insures economy of construction and maintenance, lessened noise and a saving in space.

I do not wish to be limited to the details of construction and arrangement herein shown and described, and any changes or 95 alterations may be made therein within the scope of the subjoined claims.

Having described my invention, I claim:

1. In a rotary explosive engine, a cylinder comprising a hollow shell approximately 100 elliptical in cross section, a rotor movable in said shell and adapted to slidably engage the inner surface of the latter at opposite points in its minor axis, to provide a gas passage on each side thereof, a gas-inlet 105 port communicating with one passage and a gas-outlet port with the other, a series of gas-receiving pockets formed in the periphery of said rotor, a gas-igniting device communicating with the passage containing the 110 gas-outlet port, radially-movable blades spring-pressed in contact with the inner surface of the shell between said pockets, and means communicating with the passage containing the gas-inlet port, for reinforcing 115 each charge of gas presented by a pocket to the gas-igniting device.

2. In a rotary explosive engine, a cylinder comprising a hollow shell approximately 120 elliptical in cross section, a rotor movable in said shell and adapted to slidably engage the inner surface of the latter at opposite points in its minor axis, to provide a gas passage on each side thereof, a gas-inlet port communicating with one passage and a gas- 125 outlet port with the other, gas-receiving pockets formed in the periphery of said rotor, radially-movable blades spring-pressed in contact with the inner surface of said shell, means in the exhaust passage 130

of the latter for igniting the gas carried by said pockets, and a chamber formed above the inlet passage of the shell, and in communication therewith, for delivering to each pocket a reinforcing charge of gas.

5. In a rotary explosive engine, a cylinder comprising a hollow shell approximately elliptical in cross section, a rotor movable in said shell and adapted to slidily engage the inner surface of the latter at opposite points in its minor axis, a passage formed on each side of said axis, whose walls converge at each end thereof, a gas-inlet port communicating with the lower end of one passage and a reinforcing chamber with its upper end, a gas-outlet port communicating with the lower end of the other passage and gas-igniting means with the upper end thereof, a series of gas-receiving pockets formed in the periphery of said rotor, and radially-movable blades carried by the latter, spring-pressed in contact with the inner surface of the shell, two of said blades being disposed between each pair of pockets to sweep gas into said reinforcing chamber, from which it escapes to the piston pockets to increase the charge therein.

4. In a rotary explosive engine, a cylindrical shell having a smooth inner surface approximately elliptical in cross section, an integral head on one side thereof and a removable head on the other, a shaft journaled in bearings provided in the central portions of said heads, a rotary piston keyed to said shaft within the shell and adapted to slidily engage the inner surface of the latter at opposite points in its minor axis, a series of gas-receiving pockets formed in the periphery of said piston, radial grooves extending into the latter between said pockets, blades movable into and out of said grooves, springs mounted in recesses provided in said piston, to continuously press said blades against the inner surface of the shell, a gas passage formed between the piston and shell on each side of the latter's minor axis, an inlet port communicating with the lower end of one passage and an outlet port with the lower end of the other passage, a gas storage chamber at the upper end of the inlet passage and a spark plug at the upper end of the other passage, said storage chamber receiving from the inlet passage gas which it later delivers to each piston pocket, to reinforce the charge therein for explosion by the spark plug.

5. In a rotary explosive engine, a cylindrical shell having a smooth inner surface approximately elliptical in cross section, an integral head on one side thereof and a removable head on the other, a shaft journaled in bearings provided in the central portions of said heads, a rotary piston keyed to said shaft within the shell and having an outer rim adapted to slidily engage the inner

surface of the latter at opposite points in its minor axis, an annular partition in said piston providing an annular cavity on each side thereof, radial grooves extending from the periphery of said piston to the outer cavity, 70 grooves in alinement with said first named ones extending through said partition, blades movable in said corresponding grooves, springs mounted between said partition and abutments on said blades, to force the outer 75 ends of the latter in continuous engagement with the inner surface of said shell, while the lower ends of said blades extend into the inner cavity of the piston, a gas passage formed between the piston and shell on each 80 side of said minor axis, a gas-inlet port for one passage and a gas-outlet port for the other, a spark plug communicating with the outlet passage, and peripheral pockets formed in said piston into which gas is compressed by said blades, for explosion by said spark plug.

6. In a rotary explosive engine, a cylindrical shell having a smooth inner surface approximately elliptical in cross section, an integral head on one side thereof and a removable head on the other, a shaft journaled in bearings provided in the central portions of said heads, a rotary piston keyed to said shaft within the shell and having an outer rim adapted to slidily engage the inner surface of the latter at opposite points in its minor axis, an annular partition in said piston providing an annular cavity on each side thereof, radial grooves extending from the periphery to the outer cavity of said piston, 90 grooves in alinement with said first named ones extending through said partition, blades movable in said corresponding grooves, each blade having the contour of a paddle whose 95 lower end terminates in three leg sections, a spring surrounding each middle leg section, and extending from said partition into a peripheral recess formed in the piston rim, said recess being of sufficient size to permit said 100 spring to press its respective blade against the inner surface of the cylinder shell, the leg sections of each blade extending below the spring, which bears against the said partition, into the inner cavity of the piston, a 105 gas passage formed between the piston and shell on each side of said minor axis, a gas-inlet port for one passage and a gas-outlet port for the other, a spark plug communicating with the outlet passage, and peripheral pockets formed in said piston into 110 which gas is compressed by said spring-pressed blades, for explosion by the spark plug.

7. In a rotary explosive engine, a cylindrical shell having a smooth inner surface approximately elliptical in cross section, an integral head on one side thereof and a removable head on the other, a shaft journaled in bearings provided in the central portions 115

125

130

135

- of said heads, a rotary piston bored from one side thereof to form a central core, to which said shaft is keyed, an annular partition formed above said core to provide a cavity on each side thereof, a circular rim for said piston whose periphery slidingly engages the inner surface of said shell at opposite points in its minor axis, a circular plate secured to the open side of said piston, radial 5 grooves extending from the periphery to the outer cavity of said piston, grooves in alignment with said first named grooves extending through said partition, blades movable in said corresponding grooves, springs seated 10 against said partition, adapted to press said blades into continuous engagement with the inner surface of said shell, a gas passage formed between the piston and shell on each side of said minor axis, a gas-inlet port at 15 the lower end of one passage and a reinforcing chamber at its upper end, a gas-outlet port at the lower end of the other passage and a spark plug at the upper end thereof, the walls of the inlet passage converging 20 from the major axis of the shell toward said reinforcing chamber, whereby gas may be swept therein by the radially movable blades, and peripheral pockets formed in said piston between the blades to receive gas from 25 30 the inlet port and reinforcing chamber to conduct the same to the spark plug for explosion.
8. In a rotary explosive engine, a cylinder comprising a hollow shell, inclosing heads 35 therefor, a rotor movable in said shell, radially movable piston members carried by said rotor, in continuous engagement with the inner surface of said shell, the side edges of said members being beveled, and packing 40 pieces slidingly movable along the beveled side edges of said members, into engagement with the inclosing sides of the rotor, to prevent leakage between the latter and the piston members.
- 45 9. In a rotary explosive engine, a cylinder comprising a hollow shell approximately elliptical in cross section, inclosing heads therefor, a rotor movable in said shell, radially movable piston blades carried by said 50 rotor, resilient means for forcing said blades in continuous engagement with the inner surface of the shell, the side edges of said blades being beveled, and packing pieces 55 slidingly movable along the beveled edges of said blades into contact with the sides of the rotor, to prevent leakage between the latter and the blades.
- 60 10. In a rotary explosive engine, a cylinder comprising a hollow shell approximately elliptical in cross section, inclosing heads therefor, a rotor movable in said shell, radially movable piston blades carried by said rotor, spring-pressed into engagement with the inner surface of the shell, the side edges 65 of said blades being triangular in cross sec-
- tion, and packing pieces having recessed sides adapted to loosely receive the side edges of the blades, whereby, when subjected to pressure, they will be slidingly moved along the beveled edges of the latter into 70 contact with the rotor sides, to prevent leakage between the latter and the blades.
11. In a rotary explosive engine, a cylinder comprising a hollow shell approximately elliptical in cross section, inclosing heads 75 therefor, a rotor movable in said shell, radially movable piston blades carried by said rotor, the side edges of the blades being beveled, packing pieces adapted to be slidingly moved, by pressure, along the beveled edges 80 of the blades, into engagement with the sides of the rotor, and split rings between the upper portions of said packing pieces and cylindrical shell to prevent leakage past the rotor.
- 85 12. In a rotary explosive engine, a cylinder comprising a hollow shell approximately elliptical in cross section, an integral and a removable head therefor, a rotor movable in said shell, radially movable piston blades 90 carried by said rotor, elongated packing pieces interposed between the sides of the blades and rotor, a split ring, triangular in cross section, disposed between the packing pieces, the rotor wall and integral-head side 95 of the shell, and a split ring, rectangular in cross section, disposed between the packing pieces, rotor side and that side of the shell which is closed by the removable head, to seal openings through which the explosive 100 mixture might escape.
13. In a rotary explosive engine, a cylinder comprising a hollow shell approximately elliptical in cross-section, an integral and a removable head therefor, radially movable blades 105 carried by said rotor, spring-pressed against the inner surface of the shell, elongated notches provided in the sides of said blades, elongated packing pieces loosely fitted in said notches, and having grooved side edges 110 adapted to loosely receive the side edges of the blades, which are triangular in cross section, a split ring, also triangular in cross section, disposed between the packing pieces, the rotor wall and integral-head side of the 115 shell, and a split ring, rectangular in cross section, disposed between the packing pieces, rotor side and side of the shell which is closed by the removable head, to seal openings through which the explosive mixture 120 might escape.
14. In a rotary explosive engine, a cylinder comprising a hollow shell approximately elliptical in cross section, an integral and a removable head therefor, a rotor movable in 125 said shell, said rotor being bored out from one side thereof to provide two annular cavities therein, radially movable blades extending through grooves in the rotor into said annular cavities, springs mounted in the ro- 130

tor for pressing said blades in continuous engagement with the inner surface of the shell, a circular plate closing the open side of said rotor, elongated notches provided in the sides of said blades, elongated packing pieces movably fitted in said notches, and having grooved side edges adapted to loosely receive the side edges of the blades, which are triangular in cross section, a split ring 10 also triangular in cross section, disposed between the packing pieces, the integral rotor-

side and the shell, and a split ring, rectangular in cross section, disposed between the packing pieces, rotor plate and shell, to seal openings through which the explosive 15 mixture might escape.

In testimony whereof I have hereunto set my hand this 20th day of November, 1915.

MAX C. WHITMORE.
